FIG. 2.

THE. 8.

This technical drawing illustrates a cross-sectional view of a mechanical assembly. On the left, a vertical cylinder with a ribbed side is labeled '106'. A horizontal rod or tube passes through the center of this cylinder. The tube is labeled with numbers '111', '115', '113', and '112' from left to right. At the right end of the tube, there is a complex assembly of gears and a central shaft. This assembly includes a gear labeled '120', a gear labeled '121' below it, and a gear labeled '118' and '116' above it. A small circle is drawn on the tube near the center of the assembly. The entire assembly is labeled with the number '114' at the bottom right. Below the main assembly, there is a horizontal structure with rectangular cutouts, labeled '111', '112', and '113' from left to right. The entire drawing is enclosed in a rectangular border.

RIVETING MECHANISM

Louis C. Huck, Buchanan, Mich., assignor to
Huxon Holding Corporation, a corporation of
Michigan

Application March 6, 1936, Serial No. 67,458

14 Claims. (Cl. 218—19)

This invention relates to a rivet setting machine adapted to set the type of rivet disclosed in the applications of Louis C. Huck, Serial No. 627,343, filed August 3, 1932, now Patent No. 2,061,628 issued Nov. 24, 1936; Serial No. 681,362, filed July 20, 1933, now Patent No. 2,061,629 issued Nov. 24, 1936, and the particular form of the rivet disclosed in Serial No. 21,473, filed May 14, 1935.

An object of the invention is to provide a single anvil rivet gun for setting the above type of rivet as distinguished from the double anvil guns shown in the application of Louis C. Huck et al., Serial No. 636,480, filed October 6, 1932, now Patent No. 2,053,719 issued September 8, 1936, and the applications of Louis C. Huck, Serial No. 21,472, filed May 14, 1935, and Serial No. 21,474, filed May 14, 1935, now Patent No. 2,088,859 issued August 3, 1937, and to provide a single anvil gun which is adapted to set a rivet in the manner set forth in the application of Louis C. Huck, Serial No. 21,473, filed May 14, 1935.

One object of the invention is to provide an improved anvil construction for a single anvil gun of the type disclosed in the aforesaid application, Serial No. 21,473.

Another object is to provide means in conjunction with a single anvil rivet gun to eject the rivet head from the anvil.

Another object of the invention is to provide a greatly simplified and more powerful single anvil rivet gun of the type mentioned.

Another object is to provide a scavenging means whereby any air or other foreign matter in the operating fluid will be removed from the gun during the normal operation thereof.

Another object is to provide an improved trigger and handle construction adapted to be readily operated in any position of the gun.

Another object is to generally improve the details of construction in order to provide a gun which is relatively inexpensive, rugged and easy to assemble.

Other objects and advantages of the invention will become apparent from the accompanying drawings, specification and the appended claims.

In the drawings wherein like numerals are applied to like parts in the several views:

Figure 1 is a longitudinal vertical section of the gun showing its internal construction.

Figure 2 is a plan view of the gun, partly broken away.

Figure 3 is an end view of the operating end of the gun.

Figures 4, 5, 6, 7, 8 and 9 are transverse sec-

tional views taken on the line 4—4, 5—5, 6—6, 7—7, 8—8 and 9—9 of Figure 1, respectively.

Figure 10 is a longitudinal section taken on the line 10—10 of Figure 3.

Figure 11 is a horizontal section looking upwardly and taken on the line 11—11 of Figure 1.

Figure 12 is a side elevation of the sleeve which carries the pin gripping element showing in elevation the structure illustrated in section in Figure 4, with a portion of the outer casing broken away.

Figures 13, 14 and 15 are enlarged sectional views of the anvil end of the gun, corresponding to the section shown in Figure 1, and illustrating three different operating positions of the mechanism.

Figures 16, 17 and 18 illustrate, respectively, modified forms of the anvil and rivet head ejecting elements.

Fig. 19 is a diagrammatic view of the rivet gun and pressure supply means therefor.

Referring to Figure 1, the gun illustrated comprises a casing 10 provided with an enlarged longitudinal opening therethrough for the reception of an operating piston 11, and as shown by Fig. 11, the upper part of the casing is provided with a pair of smaller longitudinal bores 12 and 13. As shown in the latter figure, the bore 13 is threaded at one end to receive a threaded coupling member by means of which a pressure fluid conduit 14 may be connected in communication with the bore. The bore 12, at the corresponding end thereof, is likewise provided with a coupling member by means of which it is connected to a pressure fluid conduit 15. These pressure conduits are connected to a suitable source of pressure through a control valve which is operable in one position to supply fluid under pressure, to one conduit and at the same time to connect the other conduit to exhaust, and which is operable in another position to supply fluid under pressure to the latter conduit, and at the same time to connect the former conduit to exhaust.

Such pressure supply means and control valve is disclosed in detail in the copending application of Louis C. Huck, Serial No. 21,474, filed May 14, 1935. As shown diagrammatically in Fig. 19 of the present application, this means comprises a fluid reservoir 1, a pump 2, a control valve 3 having operating solenoids 4 and 5, and a pressure booster cylinder 6, connected by suitable conduits with each other and to the gun. The arrangement is such that, in one position of the control valve, fluid is supplied from the pump through the control valve to conduit 15 while the conduit 14 is connected through the valve to the exhaust.

reservoir. When the valve is shifted from said position by the solenoid 5, the pump supplies fluid through the valve to the large cylinder 8 of the booster and the small cylinder 9 of the booster is placed in fluid communication with conduit 14. At this time conduit 15 is connected through the valve to the exhaust reservoir. It will be apparent that as the solenoids are alternatively operated first one of the conduits 14 and 15 will be connected to a source of fluid under pressure while the other is connected to exhaust and then the first will be connected to exhaust while the other is connected to a source of fluid under pressure. Moreover, the pressure supplied to the conduit 14 will be augmented by the booster 6.

As shown best in Figure 1, the handle, indicated generally at 16, comprises an attaching portion 17 secured to the top of the casing by any suitable means, such as stud bolts 18, and a hollow hand engaging portion 19 connected integrally at each end to the corresponding end of the attaching portion 17 by curved connecting portions 20 and 21 respectively. It will be noted that the hand engaging portion is symmetrically proportioned with respect to the axis of the gun and is parallel therewith. In addition, the handle is positioned above the center of gravity of the gun in order that the gun will remain in a level position when supported by the handle during horizontal riveting. Adjacent the opposite ends of the hand engaging portion the under side thereof is cut away at 22 and 23 to provide openings for the reception of trigger members 24 and 25, respectively. These trigger members are identical; although oppositely disposed, and each is connected to a leaf spring 26 adjacent the opposite ends of the latter. This connection is effected by inserting one end of the spring in a slot 28 in the upper side of the trigger and securing it in position therein by means of a pair of pins 29 carried by the trigger member. The opposite ends of the leaf spring 26 are mounted in slots 30 in the handle portions 20 and 21 respectively, and are held in fixed position with respect to the handle by clips 31 which in turn are secured to the handle by means of studs 32 and extend into slots in the ends of the leaf spring at 33. The leaf spring extends through the hollow portion of the handle and its intermediate portion is twisted 90° with respect to the vertical end portion, as at 34, to provide increased flexibility in a vertical plane and has an offset U-shaped central portion 35 engaging a pin 36 carried by the handle portion 19.

For the purpose of limiting movement of the trigger elements upwardly and thereby preventing possible damage to the leaf spring and switch element 37 as well as other parts of the switch, a stop 40 is provided above each trigger. Thus, even if the operator presses very hard on the trigger, the flexing of the spring and actuation of the switch is effected the same as if the trigger were moved easily against the stop. This arrangement is designed to promote durability of the switch actuating parts while at the same time to insure positive actuation of the switch.

It will be observed that by reason of the symmetrical proportioning and position of the handle that it may be grasped readily in any position of the gun. Moreover, since the trigger members are duplicated and are likewise symmetrical with respect to the main hand engaging portion, one of said trigger members will be in position to be grasped and operated by the in-

dex finger of the hand regardless of the position of the gun.

When it is desired to initiate the action of the gun, either one or the other of the trigger members may be pressed. This flexes the intermediate portion of the spring 26 upwardly into operative engagement with an actuating element 37 of a suitable electric switch 38 positioned within the hollow portion of the handle and fixed to the handle by means of pins 39. The switch may be any suitable single pole double throw switch adapted to alternatively energize one or the other of the solenoid operating elements disclosed in the aforementioned application, Serial No. 21,474. The switch is designed to maintain the circuit closed through solenoid 4 so long as pressure is applied to one of the triggers, but will open that circuit and close the circuit to the opposite solenoid 5 when the pressure on the trigger is released. As the result of this arrangement the conduit 15 will normally be connected to the source of pressure while the conduit 14 is connected to exhaust. When the trigger is pressed, however, conduit 15 is connected to exhaust and the conduit 14 is connected to the high pressure cylinder 7 of the booster.

The bore 13 is in constant communication with the left hand end of the main operating cylinder through a port 41, as shown in Figures 1 and 7, while the bore 12 is in constant communication with the right hand end of the main operating cylinder through port 42, as shown in Figures 1 and 8. Thus, when fluid pressure is applied to the bore 13, it will be effective upon the left hand end of piston 11, and will move the piston to the right, as viewed in Figure 1, while application of fluid pressure through the bore 12 will effect return movement of piston 11 to the left.

It will be noted that by reason of the fluid pressure operating connections so far described, reciprocation of piston 11 in the main cylinder will be accompanied and caused by reciprocation of liquid columns in the bores and conduits respectively. Some liquid will be exhausted from one conduit at that end remote with respect to the gun during each stroke of the piston and likewise additional liquid will be supplied to the end of the other conduit. If the conduits are short, some liquid in the gun will be also exhausted and likewise fresh liquid will flow through the other conduit into the gun. On the other hand if the conduits are long, the liquid in the gun normally would remain in the gun and conduits and only liquid columns in the exhaust and supply ends of the conduits, that is the ends remote from the gun, would be exhausted and resupplied with fresh oil. Under any set of circumstances where the same liquid is apt to remain in the gun, it is desirable to obtain a replacement of this liquid, or else any dirt and other foreign matter, and especially air, which might collect in the gun, would permanently be trapped. To obtain this replacement of liquid in the gun, a scavenging valve is provided that will cause a progressive change of the liquid during repeated operation of the gun or a slow constant change during idle periods of the gun, provided of course in the latter case that the pump or other pressure developer is constantly operating.

The scavenging valve, as best shown in Figures 10 and 11, is shown positioned within the left hand end of the low pressure bore 12. It will be noted that the bore 12 at its left hand end is somewhat enlarged to provide a shoulder 45 and 70

75

that the enlarged portion opens to the left face of casing 10. Positioned within the enlarged portion of bore 12 and seated against shoulder 45 is an annular member 46 having a small axial bleed opening 47. A valve cage 48 is seated against member 46 and a packing ring 49 is positioned between these members to prevent leakage along the wall of the bore. The valve cage 48 is held against the packing 49 by means of an assembly 10 comprising a flanged tubular member 50, which is seated against cage member 48, a packing ring 51 seated against member 50, a cap member 52 which is seated against the packing ring 51, and a screw threaded plug 53 which is screwed into the open end of the enlarged portion of bore 12 and bears against the cap 52. The valve cage 48 has an axial bore for the reception of a sliding valve 54, and an axial port 55 of smaller diameter than said bore, and in communication therewith. The juncture between the bore for receiving valve 54 and port 55 forms a shoulder against which a reduced end portion of valve 54 is adapted to bear, and thus limits movement of the valve to the right. The cage member 48 is provided with a lateral port 56 in communication with the interior of the cage, a circumferential recess 57 in its outer periphery, and a longitudinal external groove 58 providing fluid communication between port 56 and recess 57. Recess 57 is in fluid communication with the left hand end of the interior bore of cage member 48 through a radial slot 59 in the end of the cage member, and is also in communication with the left hand end of the main cylinder bore of casing 10 through a diagonal conduit or port 60, shown in Figure 10. Valve 54 is provided with a stem 61, and a helical spring 62, positioned within a housing formed by members 50 and 52, surrounds the stem 61 and bears at its opposite ends on the valve 54 and the cap 52 respectively, thus urging the valve member to the right as viewed in Figures 10 and 11.

When liquid pressure is applied through bore 13 to the left hand side of the operating piston 11, it acts by reason of port 60, recess 57, groove 58, and slot 59, on the left hand end of valve member 54. Since bore 12 is open to the exhaust tank at this time, the valve will be held in closed position and against the shoulder around port 55 and no fluid can flow from bore 13 into bore 12. However, when the operating connections are reversed and liquid pressure is applied to bore 12 and exhaust to bore 13, the fluid in the low pressure bore 12 will leak through the bleed opening 47 and build up sufficient pressure at the right hand side of valve 54 to shift this valve to the left against the pressure of spring 62 thus opening communication between port 55 and port 56 of the valve cage 48. When this occurs a limited quantity of the fluid in bore 12 will flow through bleed opening 47, port 56, groove 58, recess 57, and port 60 to the left hand end of the operating piston 11. This limited flow from the bore 12 into the left hand end of the main operating cylinder is insufficient to interfere with the normal return movement of the piston under the influence of low pressure at the right hand side thereof, but it is effective to carry air or other foreign material which may be trapped in the fluid in bore 12 over into the left hand end of the main cylinder, where it can exhaust into the bore 13 through port 40. During succeeding operations of the gun this fluid with any entrapped air or foreign matter will progress back through the conduit 14 line to the storage reservoir or tank. In the

event any air tends to remain in the cylinder, it tends to disperse in the liquid (oil) during movement of the piston back and forth, and by replacing the oil, the air also is removed in this manner. During idle periods when the gun is not operated, but the pump is running, a constant scavenging action will take place as the liquid will constantly flow through the bore 12 and leak through the opening 47 and pass through the scavenging valve. 5 10

Piston 11 is forged integrally with a tubular piston rod having a section 70 to the left of the piston, as viewed in Figure 1, which is of smaller external diameter than the section 71 at the right hand side of the piston. Leakage past the piston 15 rod section 71 is prevented by a packing gland comprising a gland nut 72 threaded into the casing 10 and bearing against suitable packing rings 73 which surround the piston rod and seat against an internal radial projection 74 adjacent the right 20 hand end of the operating cylinder.

The gland nut has an annular series of castellations 75, as shown in Figure 9, into which a tool may be inserted to tighten the gland. Means for locking the gland nut in adjusted position are 25 provided comprising a recess 76 adjacent the bottom portion of the casing 10 into which is inserted a locking member 77 having a projection adapted to extend into one of the notches between the annular series of castellations. The 30 locking member 77 is held in position by any suitable means, such as a cotter pin 78, as shown in Figure 9.

A bearing or guide sleeve 80 is provided exteriorly of the packing gland for guiding the piston rod section 71. This bearing member is held in position against an abutment on the casing by means of an annular nut 81 which is threaded into the opening in the casing 10. The annular nut 81 has a tubular extension 82 upon which is 35 carried a guard member 83 secured in position by any suitable means such as a split ring having ears 84 through which a tightening bolt 85 is inserted. At its outer end the guard 83 is curved downwardly and then reversely as indicated at 40 86 and 87 respectively and the purpose of this construction will presently be described. 45

The left hand end of the operating cylinder is closed by means of a cylinder head 90 seated against a shoulder on the casing and held in 50 position thereagainst by means of an annular hexagonally headed nut 91 which is threaded into the casing. The nut 91 is provided with a plurality of radially extending holes 97 adjacent its outer face, and a wire 98 is passed through 55 one of these holes and through a hole in the adjacent edge of the casing. The ends of the wire are twisted together as shown in Figures 2 and 3, to prevent accidental rotation of the nut. The cylinder head 90 is provided with an elongated tubular extension 92 within one portion of which is mounted a packing gland comprising a gland nut 93 having an annular series of castellations 93' for the reception of a suitable tool for turning the nut, and having a portion bearing against a series of packing rings 94 which seat against an internal shoulder in the cylinder head opening. The tubular extension 92 of the cylinder head 90 is provided with a longitudinally extending slot 95 into which a tool may be inserted for engaging the castellations on the gland nut; and a retaining ring 96 is carried in a circumferential groove on member 92 and has one end thereof extending through slot 95 into engagement with the recess between two adjacent 60 65 70 75

castellations on the gland nut to maintain it in adjusted position, as shown in Figure 6.

Outwardly of the gland nut 93, the tubular member 92 is provided with an internal shoulder 5 against which is seated a bearing or guide sleeve 100 for the piston rod section 70. Bearing sleeve 100 is held in position against the internal shoulder on the tubular extension 92 by means of an annular nut 101 which is threaded into the 10 tubular extension 92 and which is provided with an annular series of castellations 102, as shown in Figure 5. Member 92, adjacent the castellations in nut 101, is provided with an annular series of radial openings 103, and a spring retaining ring 104 is positioned within an internal groove in the series of annular castellations on nut 101 and has a bent up extension 105 extending into one of the radial openings 103 of the tubular extension 92.

20 A barrel 106 is provided with an enlarged end section 107 which is telescoped over the end of tubular extension 92 and threaded thereto at 108. The thread bearing end of the barrel section 107 is provided with a hexagonal exterior periphery 25 as shown in Figure 5 for engagement with a wrench, and the internal shoulder adjacent the juncture of the smaller and larger sections of the barrel is seated against the end of tubular extension 92, at 109.

30 A pin gripping means is connected to the left hand end of the piston rod section 70. This means comprises a plurality of jaw members 110 of the type disclosed in the aforementioned co-pending application, Serial No. 21,474. These 35 jaw members, three in number, are loosely positioned within a jaw pulling sleeve 111, and the jaws and sleeve 111 have inclined co-acting faces whereby the application of a pulling force by said sleeve effects an inward radial movement of the 40 jaw members. The sleeve 111 is threaded on a sleeve member 112, and a suitable locking means is provided for locking sleeve members 111 and 112 against relative rotation. This locking means, as shown in elevation in Figure 12, comprises a ring 113 having oppositely offset portions 114 and 115 adapted to engage respectively in a notch 116 in sleeve 111 and in one of a plurality of notches 117 in a shoulder on sleeve 112. Four circumferentially spaced holes 118 are 45 provided in sleeve 111 to be engaged by a tool for rotating the same when the locking member 113 has been removed.

50 As shown in Figures 1, 4 and 12, sleeve 112 is threaded on the left hand end of the piston rod section 70, and is locked in position thereon by 55 means of a pair of tapered pins 120 and 121, which are driven into suitable openings 122 and 123, respectively, in the enlarged end of sleeve 112. These openings at their midpoints intersect the opening within sleeve 112, and at the 60 points of intersection the pins engage a ring 124 of soft metal which surrounds piston rod section 70 and bears on a series of axially extending serrations in the piston rod, not shown. It will be observed that when pins 120 and 121 are driven 65 into these openings, sleeve 112 and the associated sleeve 111 will be locked to the end of the piston rod section 70, but that when necessary they may be readily removed therefrom.

70 A relatively heavy jaw follower 130 is slidably carried within the cylindrical portion of sleeve 111 and is adapted to be contacted by jaws 110. A spring 131 bears at one end against sleeve 112 and at the other end against an internal shoulder 75 on the inertia member 130 and holds the latter in

engagement with jaws 110. A guide sleeve 132 for spring 131 is held in position against the end of piston rod section 70 by an internal shoulder on sleeve 112.

As best shown in the enlarged Figure 13, the 5 left hand extremity of barrel 106 carries an annular anvil supporting block 135 which is threaded into the end of barrel 106 and bears tightly against an annular member 136, which in turn is seated against an internal shoulder 137 10 on the barrel 106. An annular anvil 138 is seated within the opening in block 135, and is provided with an external shoulder adapted to seat against a corresponding shoulder in that opening. The opening within anvil 138 is provided with an 15 annular conical outwardly flared mouth forming an inclined working surface 139 adapted to engage a corresponding surface on the head 140 of the tubular member 141 of the two part rivet. As set forth in the aforementioned application, 20 Serial No. 21,473, this anvil is adapted when the reaction force increases beyond that required to form the head on the opposite end of the tubular member to advance over and swage head 140 onto the rivet pin 142.

An ejecting member 150 is slidably mounted within the cylindrical portion of the opening in anvil 138 and is adapted to surround the rivet pin 142. A shoulder 151 on the ejecting member is adapted to engage a corresponding shoulder on 30 the opening within anvil supporting members 135 as well as the inner face of the anvil itself and limit movement of the ejecting member to the left, as viewed in the drawings. An opposed shoulder 152 on the ejecting member is adapted to engage the annular member 136 and limit movement of the ejecting member to the right with respect to the anvil. The left end of the ejecting member is adapted to engage the end face of the rivet head 140 and this in conjunction 35 with the shoulder 152 engageable with the member 136, provides an efficient means for positively preventing further swaging movement of the anvil after sufficient swaging is effected. It has been found that under certain conditions, the 40 anvil should engage the plate to effect the desired swaging movement and, therefore, it is desired that the ejecting member be arranged to permit sufficient movement of the anvil to accomplish the swaging necessary.

The ejecting member at its inner end has an 45 abutting surface 153 adapted to engage the end of sleeve 111. Upon completion of the rivet setting and swaging operation, and after the trigger is released, sleeve member 111 will advance to 50 the left with respect to barrel 106, during which movement it will come into abutment with the surface 153 on the ejecting member 150. Since the latter will engage the rivet head, the fluid pressure in the casing 10 will act against the right 55 end of the cylinder and move the casing, barrel 106 and anvil 138 away from the rivet head as shown by Fig. 15. In this way, the anvil is freed from any grip it may have with the rivet head.

In Figure 16 is shown a slightly modified form 60 of the ejecting member and anvil mounting. In this figure the anvil 155 is mounted directly upon an end portion of sleeve member 106. The anvil is formed as before except that at its inner end it is provided with an internal radially extending 65 shoulder 156. The ejecting member 157 is provided with a pair of external axially spaced radially extending shoulders 158 and 159 adapted to engage with shoulder 156 to limit the movement of the ejecting member with respect to the 70 75

anvil for the purposes set forth above in connection with the structure shown in Figures 13 to 15. It will be noted that the inner flange or shoulder 159 on the ejecting member is made of a separate piece and the latter is either press fitted on the ejecting member or the end of the latter may be peened over to lock the piece in place. In this modification, as in the ejecting member shown by Fig. 13, the mouth of the opening in the ejecting member is provided with an outwardly flared conical annular mouth which is adapted to assist in inserting the end of a rivet pin within the gun and into engagement with the gripping member. This form of the invention functions in the manner indicated with respect to that previously described.

In Figure 17 there is shown a further modification wherein the ejecting sleeve 160 is provided with a radially extending flange 161 having an enlarged tubular axial extension 162 engaging barrel 106 and extending into an annular recess in the end of sleeve member 111. The tubular extension 162 of the ejecting member is preferably fixed to sleeve 111, but may loosely engage the sleeve 111, if desired. In either case the ejecting sleeve will move rearwardly, or to the right as viewed in the drawings, with respect to the anvil during the rivet setting operation and cannot be relied upon to limit the swaging movement of the anvil with respect to the rivet head. Accordingly, in this modification the swaging anvil 163 is itself provided with a shoulder 164 which is adapted to engage the end of the rivet and limit the movement of the swaging anvil over the head. During the return of the parts of the gun to normal position, sleeve 106, as previously described, moves to the left with respect to the sleeve 111, thus moving the anvil 163 to the right with respect to the ejector 160, thereby forcing the anvil away from the rivet head. In this modification the ejecting member need not have any bearing on the anvil per se. It will be noted that the anvil and ejecting member may be readily assembled, or disassembled.

In Figure 18 I have disclosed still another form of ejecting member which is similar to that disclosed in Figure 16 except that it is formed of a pair of telescoping sleeve members 111 and 172, having external flanges at their opposite ends. The two sleeved members may be secured together by a pressed fit or by welding, but in either event this ejecting member functions in exactly the same manner during operation of the gun as does that disclosed in Figure 16.

The machine just described is adapted, for example, to set a rivet such as disclosed in the co-pending application, Serial No. 21,473 mentioned above. As best shown in Figure 13, the rivet initially comprises a tubular member 141 having an enlarged head 148 upon which is provided at one end an annular conical peripheral surface 139. The rivet pin 142 is provided with a spreader ring 144 and a head 145 adapted, when the pin is pulled through the tubular member and the tubular member is held against movement, to collapse the relatively thin wall 146 of the tubular member as shown in Figure 14 to form a head at that end of the tubular member. As the rivet pin is pulled through the tubular member, the shoulder 147 on the pin, between the enlarged portion adjacent the head of the pin and the remainder of the pin which is of slightly smaller diameter, engages a corresponding shoulder on the internal wall of the tubular member and spreads the tubular member into very close con-

tact with the opening in the plates 143 and 145, as shown in Figure 14. Substantial completion of the head forming pin movement places the circumferential grooves 148 on the pin within the head of the tubular member, and it positions the 5 relatively deep circumferential groove 149 in the pin adjacent the end face of the rivet head. Thereafter the pulling force on the pin is increased and the resulting increased reaction force on the swaging anvil effects movement 10 thereof over the head with a consequent inward radial movement of the metal in the head into the grooves 148 in the rivet pin. As shown in Figure 14 the swaging movement of the anvil 138 with respect to the rivet head 140 is under way and is 15 nearly completed. It will be understood that the spreader ring expands during the setting operation and prior to breakage of the pin, so that movement of the head on the pin into the tubular member is highly resisted when the tension on 20 the pin is increased to tighten the rivet or to break the pin.

As stated previously, the arrangement of parts is such that the ejecting member, or shoulder on the anvil, as the case may be, does not act to prevent the amount of swaging desired. If it is desired to have the anvil movable to engagement with the plate 143, movement of the rivet head 140 into the anvil to permit this engagement is 30 necessary. It is to be understood therefore that 35 the ejecting member or shoulder on the anvil should permit the amount of movement of the rivet head 140 into the anvil that may be required to obtain a properly set and swaged rivet assembly. After proper swaging is effected, movement of the anvil will be resisted more highly, and tension on the pin will be increased until it 40 breaks at the break neck 143.

The machine is operated in the following manner. An assembled two part rivet comprising a 40 tubular member 141 and a rivet pin 142 is inserted into the opening in the plates and then the gun is brought into position with the head on the tubular member in abutment with the swaging anvil 138 and the grooves 154 in the end of the rivet pin 45 in juxtaposition with the corresponding grooves 158 in the jaw members 110. When the gun is in proper position either one of the triggers 24 or 25 is pressed, whereupon the pressure supply valve will supply fluid to bore 13 in the casing 50 10 and connect bore 12 to exhaust. Under these conditions fluid will flow from bore 13 through port 41 into the left hand end of the operating cylinder and will force piston 11 to the right 55 with respect to the casing. Piston 11 in its movement carries with it the section 70 of the piston rod, sleeves 112 and 111, and the gripping jaws 110. Movement of the gripping jaw sleeve 111 to the right with respect to the rivet pin will force the jaw members 110 into tight engagement with 60 the pin grooves 154 and effect a pull on the pin to the right as viewed in the drawings.

At the same time the reaction to the pressure in the left hand end of the operating cylinder will be transmitted through the cylinder head 90, 65 barrel 106, anvil supporting member 135 and the anvil 138 to the rivet head 140. The angle of contact between the anvil and the rivet head, the amount of the diameter of the head is to be reduced by swaging, and the metal employed are 70 such that no appreciable movement of the anvil with respect to the rivet head will occur until the shoulder 147 on the pin has moved through head 140, the tubular member at its left end has completely collapsed to form a head at the end, and 75

the plates are drawn tightly together, as shown in Figure 14. However, as soon as the head is formed in the left end of the tubular member the resistance to the pulling force on the pin will be very greatly increased with the result that the fluid pressure will automatically build up in the left hand end of the operating cylinder until sufficient pulling force on the pin and reaction force on the rivet head through anvil 138 has been created to drive the anvil over the head and cause a flow of the metal in the head radially inwardly into the grooves 148 of the rivet pin. Then after completion of the swaging action necessary, which may or may not require engagement of the anvil with the plate, the pin will break under increased tension at the break neck 149.

When the pin breaks, gripping jaws 110 will tend to slide backwardly due to the inherent resilience of the parts, but this movement of the gripping jaws will be materially retarded by the jaw follower 130 as well as by springs 131. The broken end of the rivet pin will then or later during repeated riveting pass on through the hollow piston rod and eventually will be ejected through member 87. The guard 83 is provided to insure that the rivet pins, when ejected from member 87, will always travel in the same direction so that they can be avoided by the operator, and the direction is so selected that the broken pin ends cannot strike the fluid conduits.

As soon as the rivet pin is broken the operator releases the pressure on the trigger member with the result that the bore 13 will be connected to exhaust and fluid under pressure will be applied to bore 12. The fluid then travels from bore 12 through port 42 into the right hand end of the operating cylinder, forcing piston 11 to the left, and the fluid at the left hand side of piston 11 is exhausted through port 41 to the bore 13. During this phase of the operation, as previously described, a small amount of the fluid in bore 12 will pass through the scavenging valve 54 and into the operating cylinder at the left hand side of piston 11, carrying with it any entrapped air or foreign matter.

During the movement of piston 11 to the left, piston rod section 70 and sleeves 112 and 111 are likewise carried to the left, and the reaction force is applied to the casing through the right hand end of the cylinder, thus forcing the casing and barrel 106 to the right with respect to the sleeve 111. This relative movement causes a thrust to be transmitted from sleeve 111 through the ejecting member to the top of the rivet head, and the reaction pulling force to this thrust is applied through the barrel 106 and is effective to pull the anvil 138 off the rivet head. This is important inasmuch as it provides a power means for removing the swaging anvil from the rivet head without in any way loosening the rivet joint.

As soon as the swaging anvil is pulled free of the rivet head the operator may apply the gun to a second rivet and repeat the cycle of operation just described.

It is apparent from the above description and the accompanying drawings that the invention comprises a machine for setting rivets of the type described which is simple and effective for the purpose described; that it effects such rivet setting by means of a single anvil; and that it provides a power ejecting means for ejecting the rivet upon completion of the head swaging operation. Moreover, the parts are so designed that they may be easily manufactured and assembled or disassembled for repair.

While there are disclosed several modifications of certain portions of the mechanism, it is obvious that other modifications of the mechanism are available without departing from the spirit of the invention as illustrated and described and as set forth in the appended claims.

What is claimed is:

1. A machine for setting the type of rivet wherein a pin is pulled partially through a tubular member having a preformed head at one end to form a second head at the opposite end, including, a closed ended cylinder, a piston in said cylinder, a hollow tubular piston rod connected to said piston and extending through both ends of said cylinder, means to engage the rivet pin connected to the piston rod and having an opening therein communicating with the opening through said rod, a combined thrust member and swaging anvil fixedly secured to said cylinder, and means for supplying fluid pressure to said cylinder to effect the head forming operation, swage the preformed head to the pin, and break the pin, said pin engaging member being adapted to discharge said broken pin end through said hollow piston rod.

2. In combination, a single anvil rivet gun having a cylinder, an operating piston in said cylinder, means connected to said piston for exerting a pulling force on one rivet element, and a combined unitary thrust member and swaging anvil fixed to the cylinder and adapted to engage and transmit the reactive force to another element of the rivet, of a pair of flexible conduits connected to the cylinder and in constantly open communication with the opposite ends thereof respectively, fluid pressure means remote from said gun for alternately supplying an excess of fluid pressure to one or the other of said conduits, and means on the gun for controlling said fluid pressure means.

3. In combination, a rivet gun including a double acting cylinder and operating piston, a fluid conducting line connected to and in constant communication with the space at one end of the piston, a fluid conducting line connected to and in constant communication with the space at the opposite end of the piston, means remote from the gun operable in one position to supply high pressure fluid to the first line and permit exhaust through the second line and operable in another position to supply low pressure fluid through the low pressure line and permit exhaust through the first line, and means on the gun for controlling said last named means.

4. A machine for setting rivets of the type wherein a headed pin is pulled partially through a tubular member having a preformed head at one end to form a second head at its other end, including, means to engage the pin, an anvil adapted to engage the preformed rivet head and to swage the head to the pin by telescoping over said head, means to apply a pulling force to said pin engaging means and a reactive force to said anvil to effect the rivet setting operation and to swage the preformed head to the pin, means to reverse the direction of the applied forces on said pin engaging means and anvil, and means actuated by said pin engaging means when the direction of application of force is reversed for ejecting the preformed head from the anvil.

5. A rivet setting machine including means adapted to exert a pulling force on one rivet element, an anvil adapted to engage and swage another element of the rivet by telescoping over the same, and means for applying a force in one

direction on said first means and a reactive force on said anvil to cause the anvil to swage said other element to said first-named element, means to reverse the direction of said force to restore the parts to their initial position, and means actuated by said first means during the reverse operation to eject the other rivet element from the anvil.

6. A machine for setting rivets of the type wherein a pin is pulled partially through a tubular member having a preformed head at one end to form a second head at the other end, including, means to engage the pin, an anvil adapted to engage the preformed head and swage said head to the pin by telescoping over the head, means to apply a pulling force to said pin engaging means and a reactive force to said anvil to effect the rivet setting and swaging operations, means to reverse the direction of the applied forces on said pin engaging means and anvil, and means carried by said pin engaging means and operable when the direction of application of force is reversed for ejecting the preformed head from the anvil.

7. In a rivet setting machine, a rivet head swaging anvil, a pin gripping device, means for moving said anvil and gripping device relatively in opposite directions to drive the anvil over the rivet head and swage the head to the pin, and means operated by said pin gripping device for ejecting the rivet head from the anvil when the relative movement between the anvil and gripping device is reversed.

8. In a rivet setting machine, a casing, a rivet head swaging anvil having an opening therein and fixed to said casing, a rivet pin gripping device slidably mounted in said casing rearwardly of said anvil, an ejecting member operatively associated with said pin gripping device and extending into said opening, means for moving said pin gripping means rearwardly with respect to said anvil to drive the anvil over said rivet head, said means being reversible to move said gripping device toward said anvil and said pin gripping device and ejecting member having surfaces adapted to abut when the device is reversely moved whereby the ejecting member will advance into said anvil opening and eject the rivet head therefrom.

9. In a rivet setting machine, a casing, a rivet head swaging anvil having an opening therein fixed to said casing, a rivet pin gripping device slidably mounted in said casing rearwardly of said anvil, an ejecting member slidably carried by said casing between said anvil and gripping device and having an operative portion extending into said anvil opening, means for moving said pin gripping device rearwardly with respect to said anvil to drive the anvil over the rivet head, said means being reversible to move said gripping device towards said anvil and said pin gripping device and ejecting member having surfaces adapted to abut when the device is reversely

moved to engage said ejecting member and advance the operative portion thereof into said anvil opening to eject the rivet head from the anvil.

10. In a rivet setting machine, a casing, an annular anvil fixed with respect to said casing and adapted to swage a rivet head, an ejecting member slidably mounted in said casing, a rivet pin engaging member slidably mounted in said casing and adapted to move in one direction independently of said ejecting member to drive the anvil over a rivet head, said ejecting and pin engaging members having surfaces adapted to abut when said pin engaging member is moved in the opposite direction whereby such movement of the pin engaging member will actuate the ejecting member to effect ejection of the rivet from said anvil. 5

11. In a rivet setting machine, an anvil having an opening therein for the reception of a rivet head, an ejecting member slidably carried by said anvil in said opening, means to limit the relative movement between said member and anvil whereby said member at one limit of its motion provides an abutment for limiting the movement of a rivet head into said anvil, and movement of the member to its opposite limit ejects the rivet head, and means to move the member from said first limit to said other limit. 20

12. In a rivet setting machine an anvil having an opening therein, a rivet ejecting member mounted within said opening for sliding movement with respect to said anvil, and interengaging means on said anvil and ejecting member for limiting the relative movement of said anvil and member in both directions. 25

13. In a rivet setting machine, a rivet head swaging anvil having a rivet head engaging and swaging surface and an opening therein, means associated with said anvil apart from said swaging surface for engaging the rivet head and limiting the swaging movement of the anvil with respect to the head, and means movably mounted in said machine for ejecting the swaged rivet head from the anvil opening. 40

14. A machine for setting rivets of the type wherein a pin is pulled partially through a tubular member having a preformed head at one end to form a second head at the other end, including means to engage the pin, an anvil adapted to engage the preformed head and swage said head to the pin by telescoping over the head, means to apply a pulling force to said pin engaging means and a reactive force to said anvil to effect the rivet setting and swaging operations, 55 means to reverse the direction of the applied forces on said pin engaging means and anvil, and means carried by the anvil and actuated by said pin engaging means and operable when the direction of application of force is reversed for ejecting the preformed head from the anvil. 60

LOUIS C. HUCK.
